UNITED STATES PATENT OFFICE.

BERNARD ROUSSEAU, OF ELMIRA, NEW YORK.

FINGER GUARD FOR DIE-STAMPING PRESSES.

Application filed September 28, 1926. Serial No. 138,283.

My invention relates to a safety device, for use with hand fed and usually power-driven die-printing presses and the like, to prevent accidents to the hands and fingers 5 of an operator during hand-feeding.

An object of my invention is to automatically swing a flap outwardly from between the jaws of a press as the jaws are closing so as to push any inserted hand or fingers 10 from between the closing jaws, making it impossible for a feeder's hand or fingers to be caught between the closing jaws.

A further purpose is to support one side of a safety flap so that the other side thereof 15 is adapted to swing inwardly or outwardly between the jaws of a press according as the jaws are opening or closing, and to resiliently press the flap toward swinging inwardly between the jaws.

20 A further purpose is to pivot a resiliently "closed" flap in front of the movable jaw of a press and to angularly position the flap by its resilient engagement with the movable jaw. I prefer to use a loose pivot.

25 A further purpose is to pivotally mount a flap adapted to angular positioning inwardly and outwardly between the jaws of a press upon one side of a link pivotally carried near its other end by the movable jaw 30 and to support the mount from moving bodily with the jaw.

Further purposes will appear in the specification and in the claims.

I show two only of many practical and 35 efficient forms of my invention, and have made the selection primarily with a view to well illustrating the principles involved.

Figure 1 is a fragmentary side elevation 40 illustrating my invention applied to one type of power-driven, die-stamping press, the counter block being in raised position, preparatory to the hand insertion of a card for printing.

Figure 2 is a view generally corresponding 45 to Figure 1, but with the press in printing position, with a card in place and the safety flap in position to have prevented the possibility of a feeder's fingers having been caught between the counter block and block.

50 Figure 3 is a fragmentary section taken upon the line 3-3 of Figure 2.

Figure 4 is a perspective view of the 55 safety mechanism illustrated in Figures 1 to 3.

Figures 5, 6 and 7 are diagrammatic views

illustrating my invention applied to the same pair of co-operating blocks that are adapted to open and close, Figure 5 showing blocks open, Figure 6 the blocks partly 60 closed, and Figure 7 the blocks altogether closed.

Like numerals refer to like parts in all the figures.

Describing in illustration, and not in limitation, and referring to the drawings,—

While my invention is well adapted to use with many kinds of presses, it is particularly well suited to use with power-driven embossing and die-stamping presses, 70 and I illustrate it in Figures 1 to 4 as applied to one well-known type of power-driven die-stamping press.

The operation of the die-stamping press 75 illustrated is well understood and normally as follows:

Power is applied to the driving shaft 10 in any suitable way, (not shown).

The driving shaft is mounted in stationary supporting structure 11 of the press and carries at or near its opposite ends eccentrics 12 (one only appearing in the figures) upon opposite sides of the press, which vertically reciprocate the pressure rods 13 (of which one only is shown) to reciprocate the 85 head piece or plunger 14. The plunger 14 vertically reciprocates in a guideway 15 within the stationary frame structure, and carries at its lower end a horizontal track or slideway 16, along which an upper toggle member 17 is horizontally positioned by a rocker arm 18.

The vertically reciprocating member of the press is composite and includes the plunger 14, the upper toggle member 17 that moves back and forth along its horizontal slideway, the counter block 20 and the knuckle link 21 between the counterblock and upper toggle member.

The rocker arm 18 is pivotally supported 100 at 22 to the stationary frame structure, has pin and slot connection at 23 with the upper toggle member, and is angularly connected and operated by a link 24 which is pivotally connected at 25 to the outer end of a lever 26.

The lever 26 is pivoted at 27 to the frame structure and carries a roller 28 adapted to engage the outer surface of a cam 29 mounted upon the shaft 10. It has a depression 30.

The roller is held against the cam by 110 gravity. I have diagrammatically illustrated this pressure by a spring 31, anchored

at 32 to the frame structure and at 33 to the lever. It maintains roller contact with the cam.

In Figure 1 the head piece 14 is in its highest position. Starting here, the eccentrics upon the driving shaft slowly move the pressure rods downwardly and these correspondingly move down the head piece 14 and the counterblock 20 which is supported by the upper toggle member through the link 21 and its supporting straps 34, one on each side.

The counterblock 20 slides in a vertical guideway 35.

After the driving shaft has rotated sufficiently to bring the depression 30 of the cam 29 to the roller 28, the lever 26 swings clockwise on its pivot 27 under the action of the spring 31 or weight to maintain the roller in contact with the cam and in swinging moves the link 24 downwardly and the rocker arm 18 in clockwise direction to move the upper toggle member 17 to the right.

This motion of the upper toggle member to the right gradually straightens the toggle connection between the upper member 17 and the counter block 20, the toggle being straight during each impression. It will be seen that the range of motion of the counter-block is greater than that of the head 14 by reason of the horizontal movement of the upper toggle member 17.

The downward motion of the counter-block is thus due to the vertical motion of the head piece or plunger combined with that due to the straightening of the toggle. The final movement of the counterblock, to give the impression, is caused by the continuing movement of eccentrics 12, through pressure rods 13 and the knuckle link 21. The latter seats at its ends in sockets 35'.

On the upward stroke of the press the upper toggle member is moved to the left out of line with the counterblock by the roller being moved outwardly by the wall of the depression 30 of the cam and the eccentric gradually lifts the parts still further.

While the plunger is in raised position an operator places a card or other stock to be printed in place between the make-ready 36 upon the bottom of the counterblock and the die 37 upon the block or die chuck 38.

The sheet or card is positioned by the operator against any suitable gauge 39.

As the counterblock moves up the operator removes the sheet and puts another to place for the next impression before or during the succeeding down stroke.

In the past, it has sometimes happened that an operator's fingers are caught beneath the counter block on the descending stroke and it is to make this impossible that my device is applied to the machine.

My device as illustrated, (Figures 1 to

4) comprises a flap 40 which is loosely and pivotally supported at 41 against improper vertical motion. As shown, its opposite ends are pivotally supported on the outer ends of links 42 and 43 that are in turn pivotally carried at 44 upon the counterblock 20.

The flap is pressed at opposite ends by springs 45 so as to tend to swing beneath the counterblock. These springs are alike, each being connected at one end to the link 42 or 43 and at the other end to the flap.

The springs are in effect anchored to the counterblock in that the link is carried by the counterblock. It makes little difference whether the anchorage is made to the link or to the counterblock but I prefer anchoring them to the link as shown.

I show the pivot as vertically supported by chain 46 from a stationary projection 47 upon the frame work of the machine.

When the counterblock moves down from the position shown in Figure 1, the pivot 41 is unable to move down because of the support given by the chain 46. As a result, the front edge 48 of the counterblock slides down along the inner face 49 of the flap, swinging the flap on its pivot. The pivot does not have any considerable movement. There is a slight lateral displacement 95 due to movement of the links 42 and 43 as the counterblock goes down. A little play may be permitted by looseness of connections.

The swinging of the flap about the pivot 41 by reason of the engagement between the edge of the counterblock and the inner face of the flap pushes back from danger any hand or fingers inserted beneath the block thus preventing danger of injury.

The toe 50 of the flap may engage the card or other stock before the counter block has made an impression and in this event it will slide outwardly along the card or stock during the impression while slightly 110 lifting the pivot 41 by correspondingly swinging upwardly the links 42 and 43 and loosening the chain 46.

When in the position of impression, as shown in Figure 2, there is considerable 115 tendency for the flap to maintain its engagement with the front of the block and not to move down with respect to the block as the block rises, to go back to position under the counterblock when the counterblock 120 is raised. To avoid this danger a spring 51 carried on the block, spring-presses the link at 52, the spring being of sufficient strength to insure proper relative downward movement of the flap when the counterblock moves up.

In Figures 5 to 7 I show the invention in its broad application to any jaws or blocks 53 and 54, one of which is movable and the other stationary. The flap 55 is loosely 130

pivoted at 56 and spring-pressed so as to tend to swing into engagement with the movable block 57.

While the spring pressure maintaining engagement between the flap and the block or jaw can be effected conveniently by other means I show it as effected by a tension spring 58 anchored between the block or jaw at 59 and the flap at 60.

10 As the movable block reciprocates there is a corresponding reciprocating swinging back and forth of the flap, which maintains continual resilient engagement between the flap and the block.

15 In the position shown in Figure 5 in which the block 53 is all the way up the spring is pulling the flap into the bottom of the block while in the position shown in Figure 7 in which the block is down to the 20 counterblock 54, it is pulling the flap into the side of the block.

The flap is anchored at its pivot from moving upwardly when the block moves upwardly so that there is no necessity for a 25 spring corresponding to the spring 51 of Figures 1 and 2 to insure downward motion of the flap with respect to the block as the block moves upwardly.

In the structure of Figures 1 and 2 the 30 spring 51 will be unnecessary if the pivot at 41 be supported in any suitable way against upward motion.

35 In operation the flap swings in and out with the rise and fall of movable block, lying up out of the way when the block is in high position so as not to interfere with the feeding operation and swinging downwardly during each descent of the block, sweeping away from danger any hand or 40 fingers inadvertently beneath the block.

45 In view of my invention and disclosure variations and modifications to meet individual whim or particular need will doubtless become evident to others skilled in the art, and I claim all such in so far as they fall within the reasonable spirit and scope of my claims.

Having thus described my invention, what

I claim as new and desire to secure by Letters Patent is:

1. In a press having a pair of cooperating blocks one of which is movable and adapted to open and close toward the other, a safety device comprising a flap that is adapted to swing between the blocks when the movable block is open and to sweep back along the surface of the other block as the block closes, a pivotal support for the flap having vertical play and a spring adapted to press the flap into engagement with the 55 movable block.

2. In a press having a pair of cooperating blocks one of which is movable and adapted to open and close toward the other, a safety device comprising arms pivotally supported upon opposite sides of the movable block and extending generally forwardly to somewhat beyond the front of the block, a flap having opposite ends of one side pivotally supported upon the respective arms and 65 adapted to swing its other side between the blocks when the movable block is raised, means preventing material vertical movement of the pivot support of the flap and a spring pressing the flap to move between the 70 blocks as the movable block rises.

3. In a press having a pair of cooperating blocks one of which is movable and adapted to open and close toward the other, a safety device comprising arms pivotally supported upon opposite sides of the movable block and extending laterally to somewhat beyond the front of the block, a flap having one side pivotally supported at opposite 75 ends upon the respective arms and the other side adapted to swing on the pivot to position between the blocks when the movable block is open, a spring adapted to maintain resilient contact between the flap and the movable block, a flexible support limiting the downward position of the pivot and a second spring adapted to resiliently press the arms downwardly to prevent material motion of the pivot of the flap during upward movement of the block.

BERNARD ROUSSEAU.
